UNITED STATES PATENT OFFICE.

ANDREW CHRISTIANSON, OF BUTLER, PENNSYLVANIA, ASSIGNOR TO STANDARD STEEL CAR COMPANY, OF PITTSBURGH, PENNSYLVANIA, A CORPORATION OF PENNSYLVANIA.

CAR-DOOR-OPERATING MECHANISM.

Application filed May 6, 1922. Serial No. 558,914.

To all whom it may concern:

Be it known that I, ANDREW CHRISTIANSON, a citizen of the United States, and resident of Butler, in the county of Butler and State of Pennsylvania, have invented a new and useful Improvement in Car-Door-Operating Mechanism; and I do hereby declare the following to be a full, clear, and exact description thereof.

10 My invention relates to car door operating mechanism and has special reference to what is commonly known as the Simonton door operating mechanism for hopper bottom cars.

15 In this Simonton construction the operating shaft has a cam lever mounted thereon, a connecting bar attached to the door, and having means on it for engaging the cam lever and a link connecting the bar with one arm of the cam lever, so that when the shaft is turned the door is closed by drawing on said bar until said bar passes over and beyond the shaft, the cam lever being drawn beyond the center so as to hold the door in

20 closed position. When it is desired to release the door, the shaft is turned until the hand lever is thrown over the center, whereupon it engages said bar, and in conjunction with the weight of the load the door is

25 thrown open. In the operation of this device, however, the operator in turning the shaft was liable to receive a severe shock when the cam lever was thrown beyond the center to open the door, as there was nothing to prevent the shaft from running wild, and the crank arm was liable to hit the operator and break his arm or inflict other injury.

The object of my invention is to provide a simple arrangement by which such shock to 40 the operator may be avoided and the wear and tear of the operating mechanism greatly relieved.

In the accompanying drawing, Fig. 1 is a section on the line 1-1, Fig. 3; Fig. 2 is a 45 like view showing the door in its open position; Fig. 3 is a transverse section of half of the car between the hopper doors; and Fig. 4 is an enlarged end view of the ratchet mechanism.

50 In the drawing the numeral 2 designates center sills of an ordinary car construction with the hoppers 3 closed by the doors 4 hinged at 5 to the frame of the car.

The door operating shaft 6 is supported 55 at its outer end in the bracket 7, and the said

shaft has the ratchet wheel 8 engaged by the pawl 9 to hold the door in closed position.

The shaft 6 is supported beneath the center sills 2 by the brackets 10 which are riveted to the flanges 11 of the center sills 60 and to the angles 12 secured to said center sills, the shaft 6 being free to rotate in said bearing brackets.

Loosely mounted on the shaft 6 between the brackets 10 is the cam lever 13 which is 65 composed of the eccentric cam section 14 and the arm 15. The cam lever has the hub portions 16 and 17 through which the shaft 6 passes, and said hub portions have formed on the inside the annular grooves 18 adapted 70 to receive the lugs 19 on said shaft 6. These lugs are securely attached to the shaft 6 and may be made of hardened steel to insert in seats formed in said shaft and then welded therein. In order to introduce the lugs 19 75 into the annular grooves 18, the openings 20 in the hubs are provided through which the said lugs 19 are inserted.

Within the annular grooves 18 are the lugs 21 formed integral with the hubs 16 80 and 17 and in normal position when the doors are closed the lugs 19 are in engagement with the lugs 21 on the left side thereof, as shown in Fig. 1.

Links 22 are pivotally connected to the 85 arm 15 of the cam lever, the opposite ends of said links being pivotally connected to the hooked end portion 23 of the bar 24. The outer end of the bar 24 is connected to the eye-bolt 25 held in the bracket 26 by the 90 nut 27, the bracket 26 being secured to the channel bar 28 extending in the outer edge of the door and connecting up a pair of hopper doors one on each side of the car.

The bar 24 has the lug 29 formed thereon 95 in the path of the eccentric cam portion 14 of the cam lever, and is adapted to be engaged by said cam lever when the shaft is turned, and said cam lever acts to force the bar backwardly to aid in the opening of 100 the door.

When the door is closed the parts will be in the position shown in Fig. 1, and when it is desired to open the door the operator applies a crank to the outer end of the 105 shaft 6, and throwing the pawl 9 out of engagement with the ratchet 8 turns the shaft 6 in the proper direction. This turning of the shaft will move the lugs 19 around in the annular grooves 18 until said lugs en- 110

gage the opposite sides of the lugs 21, whereupon by further movement the cam lever will be rotated on the shaft 6 and when thrown beyond the center the eccentric portion 14 will engage the lug 29 on the bar 24, and that, in conjunction with the load in the car, will throw the door into open position. In moving the car to open position the cam lever and the links 22 will 10 assume the position shown in Fig. 2 with the door in wide-open position. By this construction it is only necessary for the operator to move the shaft 6 until the lugs 19 engage the lugs 21 and move the cam lever 15 beyond the center point, whereupon the cam lever, being free to rotate on the shaft 6, the opening of the door takes place without any further rotation of the shaft 6, and consequently no jar or strain is transmitted 20 to the operator who has hold of the crank by which he has turned the shaft 6 to effect the above result. As a consequence all danger of the shaft 6 running wild and the crank from doing injury to the operator is 25 avoided.

What I claim is:

1. In a hopper-bottom car, the combination of a hopper door hinged thereto, an operating shaft, a cam-lever loosely mounted 30 on said shaft having a hub portion with

an annular groove formed therein, a projection on said shaft engaging said groove, a lug on the inner face of said hub adapted to be engaged by said projection on said shaft, and connections between said cam-lever and said door. 35

2. In a hopper-bottom car, the combination of a hopper door hinged thereto, an operating shaft, a cam-lever loosely mounted on said shaft having a hub portion with an annular groove formed therein, a projection on said shaft engaging said groove, a lug on the inner face of said hub adapted to be engaged by said projection on said shaft, a bar connected to the door, and a link 40 45 connecting said bar with the arm of said cam-lever.

3. In a hopper-bottom car, the combination of a hopper door hinged thereto, an operating shaft, a cam-lever loosely mounted 50 on said shaft having hub portions at each side thereof with annular grooves formed therein, projections on said shaft engaging said grooves, lugs on the inner faces of said hub portions adapted to be engaged by said 55 projections on said shaft and connections between said cam-lever and said door.

In testimony where I, the said ANDREW CHRISTIANSON, have hereunto set my hand.

ANDREW CHRISTIANSON.
